M. B. WATERMAN

Des. 99,909

CRUCIFIX

Filed March 28, 1936

Inventor:
M. B. Waterman

UNITED STATES PATENT OFFICE

99,909

DESIGN FOR A CRUCIFIX

Max B. Waterman, Chicago, Ill.

Application March 28, 1936, Serial No. 61,839

Term of patent 3½ years

To all whom it may concern:

Be it known that I, Max B. Waterman, a citizen of the United States, with post office address at 526 South Dearborn Street, city of Chicago, county of Cook, and State of Illinois, have invented a new, original, and ornamental Design for a Crucifix, of which the following is a specification, reference being had to the accompanying drawing, forming part thereof.

Figure 1 is a plan view of the crucifix showing my design; and Figure 2 is a cross-sectional view taken along the lines 2—2 thereof.

I claim:

The ornamental design for a crucifix as shown.

MAX B. WATERMAN.
